UNITED STATES PATENT OFFICE.

SYLVANUS S. MORRISON, OF NEWPORT, KENTUCKY, ASSIGNOR OF NINE-TWENTIETHS
TO WALTER L. BUCKMAN, OF COVINGTON, KENTUCKY.

AUTOMATIC BALANCING MECHANISM IN FLYING-MACHINES.

972,385.

Specification of Letters Patent. Patented Oct. 11, 1910.

Application filed April 6, 1910. Serial No. 583,839.

To all whom it may concern:

Be it known that I, SYLVANUS S. MORRISON, a citizen of the United States, residing at Newport, in the county of Campbell 5 and State of Kentucky, have invented a new and useful Automatic Balancing Mechanism in Flying-Machines, of which the following, taken in connection with the accompanying drawings, is a full, clear, and exact description.

My invention relates to improvements in flying machines of the class commonly known as heavier-than-air flying machines, in which my rocking supporting surface or plane operates automatically in conjunction with a suspended car, or frame, and a shifting propeller; and the objects of my improvements are, first, to provide a safe and sure automatic lateral balancing, or equilibrium in flying machines; second, to provide a safe steering to the right or left without a vertical rudder; third, to provide means for shifting the propeller to the right or left, independently from the rocking supporting 20 surface or plane.

Other objects will be brought out in the following description.

I attain these objects by the automatic mechanism illustrated in the accompanying 25 drawings, in which—

Figure 1 is a vertical side view; Fig. 2, a vertical front view looking toward the rear of the machine; Fig. 3, a top view of the propeller turn-table; Fig. 4, a vertical 35 section of the propeller turn-table and the supporting ring; Fig. 5, a top plan of the rocking supporting surface, showing the system of bracing wires.

Similar numerals refer to similar parts 40 throughout the several views.

In the accompanying drawings, Fig. 2 represents the front view of the suspended car or frame 1, which is connected to the rocking supporting surface or plane 2, by 45 two (2) journal bearings 8, situated at the upper front and rear ends of the suspended car, and at the middle of the rocking supporting surface. To the under side of the said rocking supporting surface, is secured 50 a bearing beam 38, carrying two (2) bearing brackets 36 36, adapted to form a part of the journal bearings 8 8, (see Figs. 1 and 2.) The hangers 4 4, carrying the two (2) journal bearings 8 8, are bolted to the four (4) 55 uprights of the suspended car 1. The rock-

ing supporting surface 2, has an operating mast 5, extending downwardly through the center from a point two and one-half (2½) feet, more or less, above the said rocking supporting surface; said rocking supporting 60 surface is substantially braced by wires extending from different positions on the upper and lower sides of the same, to the operating mast 5. (See Figs. 1 and 2.)

The operating mast 5, at its lower end is 65 provided with a slotted fork 6, adapted to receive an anti-friction roller 7, which is secured to the actuating lever 8; said actuating lever is mounted loosely upon a sleeve projecting outwardly from the hub of the 70 oscillating arm 9, which forms the axis upon which the actuating lever 8, swings when it is disengaged from the automatic mechanism. Slidably connected to the oscillating arm 9, is a disengaging clutch 10, adapted to 75 engage slots on the under sides of the hubs of the actuating lever 8, and the oscillating arm 9. (See Fig. 1.) The actuating lever 8, and the oscillating arm 9, swung by the operating mast 5, turn the rocking shaft 11; 80 said rocking shaft is ball bearingly mounted upon a longitudinal bearing bar 18, which is substantially braced to the frame of the suspended car 1; the said rocking shaft 11, carries the oscillating arm 9, and the bevel 85 gear 12, said bevel gear 12, is meshed to a bevel gear 14, secured to a vertical shaft 15; the lower end of said vertical shaft is secured by a plain ball bearing attached to the bearing bar 18; to the upper end of said 90 vertical shaft 15, is secured the propeller turn-table 16, ball bearingly mounted to and upon a stationary supporting ring 17, said stationary supporting ring is bolted and substantially braced to the upper front part of 95 the suspended car or frame 1; the propeller turn-table 16, carrying the propeller 18, the propeller shaft 19, and the propeller shaft driving pulley 20, mounted upon three (3) journal bearings 21, said propeller being 100 swung by the rocking shaft 11, the bevel gears 12 and 14, and the vertical shaft 15, the propeller is automatically shifted to the right or left, when the rocking supporting surface 2, is depressed on the right or left 105 side. The current of air forced by the propeller under the depressed side of the rocking supporting surface 2, immediately returns the said rocking supporting surface to a level or horizontal position, and the propeller 110

propeller is at the same time automatically returned to the front or straight position.

The motor shaft tension bearing consists of a guiding frame 23, a bearing box 22, 5 slidably mounted thereto, and a spiral spring 24; said spiral spring is adapted to the open space between the bearing box and the guiding frame. The motor driving shaft 87, passes through the bearing box 22, and carries 10 the transmission pulley 35. When the shifting of the propeller twists the belt, the belt is made tight, and the motor shaft tension bearing is provided to overcome the tightening of the belt when the belt is twisted by the turning of the propeller to 15 the right or left. The propeller is driven by a belt passing around the pulleys 20 and 35.

The two (2) ends of the steering cable 25, 20 are connected to the lower end of the oscillating arm 9, and are carried by pulleys 26, to the steering wheel 27. The steering wheel is secured to a standard 28, in front of the operator's seat 29, and is bolted to the platform 30; said platform is braced by a cross bar bolted to the under side of the platform and secured to the frame of the suspended car 1. In the rim of the said steering wheel 27, is an annular groove, adapted to receive 30 the steering cable 25.

The disengaging clutch 10, herein referred to, has at its lower end an eyelet adapted to receive a releasing cord 31, extending downwardly to a tension pulley 32; said tension pulley being adapted to take up and give out the slack of the releasing cord 31, so that the oscillating arm 9, and the releasing cord 31, will not come in contact with each other; the said releasing cord is carried rearwardly 40 to a pulley adapted to guide the same upwardly through the platform 30, to a ring secured to the standard 28, the releasing cord being tied to said ring, and within easy reach of the operator. The slack in the releasing cord herein referred to, is provided 45 to accommodate the rocking movement of the disengaging clutch 10, when the oscillating arm 9, carrying the said disengaging clutch, is oscillated by the reciprocation of 50 the rocking shaft 11.

34, represents the space occupied by the motor.

The rear part of my flying machine is not shown in the drawings, or described in this 55 application. I contemplate filing a separate application in which my complete machine will be fully described, including certain other improvements of a very important nature.

60 Steering to the right and left is performed by turning the wheel 27, toward the side in which it is desired to go. To permit this, the steering cable 25, is crossed at the under side of the wheel 27. It is not necessary for 65 the operator to keep his hand on the steer-

ing wheel unless he is flying in a heavy or gusty wind, as the forward pull of the propeller will keep my flying machine in a straight-away course. The clutch 10, is not to be withdrawn from the lever 8, except 70 at such times when the operator desires to make a sharp and quick turn. The reason for withdrawing the clutch 10, is to reverse the action of the rocking plane 2, from its automatic connections with the swinging 75 propeller. The rocking plane 2, being set free from its automatic connections with the propeller; is raised on the right side when the propeller is shifted to the left by the wheel 27, and is raised on the left side when 80 the propeller is shifted to the right. If the disengaging clutch 10, were not withdrawn at the time a sharp and quick turn to the left is desired; the rocking plane 2, would remain depressed on the right side, this condition 85 being opposite to what is desired, as in turning to the left the rocking plane 2, must be raised on the right side so that the machine can be properly banked against the outer circle of air at the turning point; the above 90 conditions reversed, applies in making a sharp and quick turn to the right.

I am not aware that prior to my invention flying machines have been made with an automatic balancing mechanism; I, therefore, 95 do claim broadly as my invention the combination in a flying machine of an automatic balancing mechanism, having a rocking supporting surface or plane, journaly connected to a suspended car or frame, and a shifting 100 propeller, with means to operate the rocking supporting surface, and the shifting propeller automatically.

I claim—

1. In a flying machine, an automatic balancing mechanism, the combination of a 105 rocking supporting surface or plane; a suspended car or frame journaly connected to said rocking supporting surface, whereby the rocking supporting surface is agitated 110 by the wind, while the suspended car or frame always hangs in a vertical position; an operating mast carried by the rocking supporting surface, said operating mast having at its lower end a slotted fork, adapted 115 to receive an anti-friction roller; an actuating lever, carrying the anti-friction roller; an oscillating arm, carrying the said actuating lever fast and loose upon a sleeve projecting from the hub of the oscillating arm; 120 a disengaging clutch, slidably connected to the said oscillating arm, and adapted to engage slots on the under sides of the hubs of the actuating lever and oscillating arm; with means to withdraw said clutch from 125 said slots, whereby the rocking supporting surface is disengaged from the automatic balancing mechanism, allowing a sharp and quick turn to the right or left with perfect safety, substantially as set forth. 130

2. In a flying machine, an automatic balancing mechanism, the combination of a rocking supporting surface or plane, a suspended car or frame, journally connected to said rocking supporting surface; an operating mast carried by the said rocking supporting surface; a slotted fork carried by the said operating mast; an actuating lever carried fast and loose, and a disengaging clutch carried slidably, by an oscillating arm; an anti-friction roller carried by the said actuating lever; an oscillating arm carried by a rocking shaft; said rocking shaft, is ball bearingly mounted upon a longitudinal bearing bar; said rocking shaft carries at its opposite end a bevel gear, partially cut away so that it will not come in contact with the said longitudinal bearing bar, when the said bevel gear is swung by the said rocking shaft; a bevel gear adapted to mesh with the bevel gear connected to the said rocking shaft, is carried by a vertical shaft, the upper end of said vertical shaft is secured to a propeller turn-table; the lower end of the vertical shaft is secured to the forward end of the said longitudinal bearing bar by a plain ball bearing; a propeller turn-table ball bearingly mounted upon a stationary supporting ring, said ring is substantially braced to the frame of the suspended car; said propeller turn-table carries a propeller, a propeller shaft, and a propeller shaft driving pulley, mounted upon three (3) journal bearings upon the upper surface of the said propeller turn-table, substantially as set forth.
3. In a flying machine, an automatic balancing mechanism, the combination of a propeller, a propeller turn-table, a stationary supporting ring for the same; an oscillating arm carrying a disengaging clutch, and an actuating lever; said disengaging clutch having at its lower end an eyelet, adapted to receive a releasing cord; said releasing cord is carried downwardly to a tension pulley adapted to take up and give out the slack of the releasing cord; said slack is provided to accommodate the rocking movement of the said disengaging clutch, caused by the oscillating arm being reciprocated by the rocking shaft herein referred to, substantially as set forth.
4. In a flying machine, an automatic balancing mechanism, the combination of a horizontal shifting propeller; a propeller

turn-table, and a supporting ring for the same; an oscillating arm, the lower end of said oscillating arm, is adapted to receive the two (2) ends of a steering cable; a suspended car carrying the said steering cable rearwardly to a steering wheel adapted to receive the same; a means to disengage the rocking supporting surface or plane from the automatic balancing mechanism, whereby the said propeller turn-table and shifting propeller is shifted to the right or left, independently of the rocking supporting surface or plane; the rocking supporting surface being set free from the automatic balancing mechanism, is raised on the right side by the current of air from the propeller, when the propeller is shifted to the left, and the rocking supporting surface is raised on the left side when the propeller is shifted to the right, this allows the flying machine to be banked against the outer circle of the turning point without using a vertical rudder, or apparatus, other than described.

5. In a flying machine, an automatic balancing mechanism, the combination of one (1) or more operating masts extending downwardly through the center of one (1) or more rocking supporting surfaces connected to a suspended car or frame, said rocking supporting surfaces being superposed, or otherwise; a propeller mounted on a swinging shaft, with means whereby the propeller is shifted to the right or left automatically, when the rocking supporting surfaces are depressed downwardly on the right or left side by the wind agitating the said rocking supporting surfaces, substantially as set forth.

6. In a flying machine, an automatic balancing mechanism, the combination of a rocking supporting plane, an automatic balancing mechanism pivoted thereto, a propeller mounted on a swinging shaft, and means whereby the propeller is automatically shifted by the rocking of the supporting plane so that the draft of air from the propeller is directed against the depressed side of the rocking supporting plane forcing the said supporting plane to a horizontal or level position, substantially as set forth.

SYLVANUS S. MORRISON.
